United States Patent Office

Des. 230,458

Patented Feb. 26, 1974

230,458

IRON

Richard B. Hall, Glen Ellyn, and Norman A. Steinkamp,
Chicago Heights, Ill., assignors to Sunbeam Corpora-
tion, Chicago, Ill.

Filed May 26, 1972, Ser. No. 257,488

Term of patent 14 years

Int. Cl. D7—05

U.S. Cl. D7—20

FIG. 1 is a perspective view of an iron showing our new design;

FIG. 2 is a top plan view thereof;

FIG. 3 is a front elevational view thereof;

FIG. 4 is a rear elevational view thereof;

FIG. 5 is a side elevational view of the side opposite that shown in FIG. 1; and

FIG. 6 is a bottom plan view thereof.

We claim:

The ornamental design for an iron, as shown.
